PEARL-KNITTING MACHINE

Volkhart Walter Mehnert, Siegmar-Schonau, Germany, assignor to the firm Elite-Diamant-werke Aktiengesellschaft, Siegmar-Schonau, Germany, a company of Germany

Application September 14, 1936, Serial No. 100,589
In Germany July 8, 1935

3 Claims. (Cl. 66—111)

The invention relates to a pearl-knitting machine. In machines of this type a needle is moved by its needle heads at each end, by means of pushers, which engage in the needle heads. 5 Before the engagement, the needle latches must be opened and heretofore it was customary to use for this purpose a latch opener travelling along with the hook slide, transverse to the direction of movement of the needles. The adjustment of 10 the opening parts, which must fit under the latches of the needles crossing them, is difficult. Moreover, it was hitherto necessary to use covers or guards along the front edge of the needle bed to keep the needle down at the bottom of its 15 channel and this made inspection of the parts difficult and prevented the front ends of the needle channels from being reached.

This defect in the known types of pearl-knitting machines is overcome by the arrangement 20 according to the invention. The essential feature of the invention is that the needle pushers have a forwardly extending prolongation with a bottom knife edge, which is spaced from the bottom sliding edge by an amount equal to the 25 height of the needle head, the needle in its middle portion being bent up to the height of the bottom knife edge on the extension of the needle pusher, the bend continuing into such proximity to the needle head that when the coupling hook 30 is linked up with the needle head, the end of the extension rests on the bend of the needle. Thus the forwardly extending prolongation of the needle pusher fulfills a double function. First it opens the needle by passing under the latch of 35 the needle before the pusher and needle head engage with each other, second it keeps the needle down on the bottom of the needle channel as long as the needle pusher itself is kept down. The needle head is released as soon as that position 40 of the lock face arrives at the pusher which enables the latter to deflect upwards for uncoupling.

In order that, upon the return of the pushers 45 during uncoupling, the needle latches may be prevented from being closed again by the returning pushers, brushes of well known kind may be provided on the lock slide, these taking the place of the otherwise usual needle guards. During the withdrawal of the pushers, these brushes 50 sweep over the needle latches opened by the knife-edges and thereby ensure their being kept open.

The drawing shows an embodiment of the invention by way of example.

55 Fig. 1 being a cross-section through a needle

board on the machine according to the invention;

Fig. 2 a partial cross-section during the opening of a latch;

Fig. 3 a longitudinal cross-section;

Fig. 4 a cross-section during the uncoupling; and

Fig. 5 a cross-section of a special brush device.

As will be seen from the drawing, the needles 1 have an upward bend in the middle of the shank 2, the top edge of this bend being on the same level as the top edge of the needle heads 3. The pushers 4 are provided with an extension piece 6 continuing beyond the coupling hook 5, the underside of this extension piece being on a 10 level with the needle head 3 and with the offset portion of the shank 2. The pushers 4 are held down by the bridge member 8 arranged on the carriage or slide 1 and consequently the pushers in turn, by means of the extended end 6, keep the shank 2, and, therefore, the needles firmly down 15 at the bottom of the needle channel. Below, the shank 2 is cut away to such an extent that the 20 stitches are not enlarged when sliding over the needles.

The extension piece 6 has a sharp edge 9 at its 25 front end and by means of this, the latches 10 of the needles 1 can be opened, before the pusher comes to couple up with the needle, as illustrated in Fig. 2.

As Fig. 4 indicates, the uncoupling of the pusher becomes possible during the withdrawal of the needle 1 by reason of the bevelling of the edge 11 of the hook 5, that is, as soon as the pusher 4 passes under the recess 12 of the bridge 8 (see 30 Fig. 3) and is therefore able to deflect upwards.

The brush 13 indicated in Fig. 5 serves principally for preventing the latches 10 from shutting, on the return of the needles. Provided it is made of sufficient width however, it can also act as a 40 latch-opener. In this case, the edge 9 need not open the latch at all, or it only comes into operation for latches which are difficult to move and which the brush has previously been unable to open.

I claim:

1. In a pearl-knitting machine with a pair of opposite flat needle beds a plurality of double ended needles in said beds, needle pushers for moving the needles, said pushers having a forwardly projecting extension with a bottom knife edge which is spaced from the bottom sliding edge by an amount equal to the height of the needle, the needle in its central portion being bent up to the height of the bottom knife-edge on the 50 55

- extension of the needle pusher, the bend continuing into such proximity with the needle head, that when the coupling hook in the needle head is coupled, the end of the extension portion rests on the bend of the needle.
- 5 2. In a pearl-knitting machine with a pair of opposite flat needle beds without the usual needle guards in the slide, a plurality of double ended needles in said beds, needle pushers for moving the needles, said pushers having a forwardly projecting extension which is spaced from the bottom sliding edge by an amount equal to the height of the needle, the needle in its central portion being bent up to
- 10 the height of the bottom of the projecting extension, the bend continuing into such proximity with the needle head, that when the coupling hook in the needle head is coupled, the end of the extension portion rests on the bend of the needle.
- 15 20 brushes on the carriage, sweeping over the latches opened by the knife edges and thus preventing them from shutting.

3. In a pearl knitting machine with a pair of opposite flat needle beds without the usual guards on the slide a plurality of double ended needles in said beds, needle pushers for moving the needles, said pushers having a forwardly projecting extension which is spaced from the bottom sliding edge by an amount equal to the height of the needle, the needle in its central portion being bent up to the height of bottom of the projecting extension, the bend continuing into such proximity with the needle head, that when the coupling hook in the needle head is coupled, the end of the extension portion rests on the bend of the needle, the moving pushers being pressed down by means of a bridge member situated in the carriage moving over the pushers, this bridge member being provided with recesses which allow the pushers to deflect upwards for the purpose of uncoupling.

VOLKHART WALTER MEHNERT.
